UNITED STATES PATENT OFFICE

109,883

DESIGN FOR A SIGNAL DEVICE OF A PAGING UNIT SYSTEM

Isidore J. Adus, New York, N. Y.

Application February 15, 1937, Serial No. 67,667

Term of patent 3½ years

To all whom it may concern:

Be it known that I, Isidore J. Adus, a citizen of the United States of America and resident of the county of Kings, city and State of New York, have invented a new, original, and ornamental Design for the Signal Device of a Paging Unit System, of which the following is a specification, reference being had to the accompanying drawing, forming a part thereof.

In the drawing,

Figure 1 is a front view in elevation of the signal device of a paging unit system.

Figure 2 is a side elevation of Figure 1.

I claim:

The ornamental design for a signal device of a paging unit system as shown.

ISIDORE J. ADUS.
